DIAL TELEPHONE LOCK

Filed June 7, 1947

UNITED STATES PATENT OFFICE

2,469,806

DIAL TELEPHONE LOCK

Bernard Zion, New York, N. Y.

Application June 7, 1947, Serial No. 753,279

8 Claims. (Cl. 179—189)

1

This invention relates to an improved demountable lock, and more particularly to such lock adapted to secure a manually operated dial of a conventional telephone connecting with a so-called automatic switchboard, against unauthorized use in making outgoing calls.

Among the objects of the invention is to generally improve demountable locks of the character described which shall comprise few and simple parts that are readily assembled to form a rugged, dependable lock, which shall be compact and neat in appearance, which shall be relatively cheap to manufacture, which shall be easy to mount in locking position and to dismount for releasing the dial, and which shall be practical and efficient to a high degree in use.

Other objects and advantages will be in part obvious and in part hereinafter pointed out.

The invention accordingly consists of features of construction, combination of elements and arrangement of parts which will be exemplified in the construction hereinafter described and of which the scope of the application will be indicated in the following claims. In the accompanying drawings, in which is shown one illustrative embodiment of this invention—

Fig. 1 is a fragmentary top plan view of base portion of a telephone instrument showing a manual dialing device with the improved demountable lock in place effective to prevent unauthorized use in making outgoing calls, said lock being constructed to embody the invention.

Fig. 2 is a front elevational view of said fragmentary base portion showing the automatic dialing device and the improved lock in effective mounted position.

Figs. 3 and 5 are enlarged cross sectional views taken through the lock on lines 3—3 and 5—5, respectively, in Fig. 1, the key being shown inserted in position for unlocking in Fig. 3, and the key position shown in dot and dash lines in Fig. 5.

Fig. 4 is an enlarged cross sectional view taken through the lock and key on lines 4—4 in Fig. 3.

Fig. 6 is an enlarged bottom view of the lock as seen from the under side of the dial plate, only a fragmentary portion of the latter being shown, and.

Fig. 7 is a side elevational view of the improved lock in released dismounted position ready to be applied for locking the dial only a fragmentary portion of the key being shown.

Referring in detail to the drawing 10 denotes the base portion of a telephone instrument showing a manual dial 11 as used in connection with operating a so-called automatic switchboard

2

(not shown) in the well understood manner.

Said dial 11, may be of any conventional well known construction and as seen from Figs. 1, 2 and 6, has a circular rotatably mounted plate or disc 12 provided with ten spaced openings 12a whereby said plate 12 is actuated against spring means (not shown) by manual manipulation in a rotary direction as indicated by the arrow in Fig. 1 in the well known manner, for dialing telephone numbers or signals in connection with said so-called automatic switchboard. The dial 11 also includes an arcuate shaped relatively stationary stop member 13 which extends over the dial plate 12 radially inward from the periphery thereof as shown in Figs. 1 and 2. Said member 13 is spaced from the dial plate 12 a sufficient distance to permit free movement of the latter and is positioned in the path of movement of dial plate opening 12a to provide a stopping means for the selective rotary movements given the dial plate 12, in the well known manner, when making outgoing calls or signals.

In practicing the invention, to secure the dial 11 against unauthorized use in making outgoing calls, that is, to prevent the dial 11 for being actuated, there is provided locking mechanism 14 which as seen from the drawing comprises an outer housing or casing barrel 15 in which there is journaled therein a cylinder 16 fitted for rotary movement on the axis thereof.

Cylinder 16 is provided with a slot or key-hole 16a which extends axially therethrough for receiving a suitable key 17, as shown in Figs. 1, 3 and 5, said casing barrel 15 and cylinder 16 being constructed and arranged with suitably spaced sets of matching tumblers 18 extending transverse said slot 16a. Ends 18a of the sets of tumblers 18 in the cylinder 16 engage in notches 17a of the key 17 for aligning the tumblers 18 in predetermined arrangement to permit unlocking mechanism 14 by rotation of the cylinder 16 in the casing barrel 15 after inserting the properly notched key 17 as shown in Fig. 3. Ends 18b of sets of the tumblers 18 opposite ends 18a in the casing barrel 15 bear against suitable compress springs 23, said sets of tumblers 18 and the springs 23 being fitted in bored cavities as shown in Fig. 3 to permit the tumblers 18 to have sliding movement therein.

To retain the cylinder 16 in assembled position in the casing barrel 15, the upper or exposed end thereof may be made with an enlarged seating flange 16b, and the lower or under end 16c of the cylinder 16 which extends beyond the casing barrel 55 at bottom has mounted thereon a spacer collar

19, said lower end 16b being terminated by a swing arm 20. The latter may be secured in any suitable manner to turn with the cylinder 16, as for example, by providing countersunk screws 21, as shown in Figs. 5 and 6. If desired collar 19 and swing arm 20 may be integrally constructed to form a one-piece structure and be secured to turn with cylinder end 16b by pinning or otherwise.

The diameter of spacer collar 19 may be sized to be readily inserted into a dial opening 12a and the swing arm 20 located by said collar 19 to be spaced free from a ledge 15a extending longitudinally down from and integrally formed with an outer portion of the casing barrel 15 so that locking mechanism 14 when in mounted effective position, shown in Figs. 1, 2, and 3, embraces the stop member 13 in an enclosing passage 22 formed over the dial disc 12, there being provided a suitable clearance, as at 22a, for permitting the rim portion or border of the dial disc opening 12a to extend into passage 22, as shown in Fig. 3 in which the lock 14, when in an effective locking position has aligning ends of said ledge 15a and arm 20, spaced apart slightly more than the thickness of the dial disc 12 to form said clearance 22a.

With a dismounted locking mechanism 14 constructed as described above and the parts thereof assembled as shown in the drawing, the key 17 when fully inserted into the cylinder slot 16a causes the tumblers 18 to move from the dotted line to the full line positions as illustrated in Fig. 3, by lodging each of the tumbler ends 18a in one of the key notches 11a. Turning key 17 to a released position, as shown in Fig. 7, rotates the swing arm 20 to extend outwardly of the casing barrel 15, that is, 180° from the effective position shown in Fig. 3, leaving the passage 22 and clearance 22a open and ready to be put in use.

To apply the locking mechanism 14 for preventing the dial disc 11 from being manually operated and thereby lock the telephone against unauthorized use, the cylinder end 16c with the swing arm 20 is simply inserted through the disc opening 12a adjacent the stop member 13 and the mechanism 14 seated on the stop member 13 with the latter extending through the passage 22 and a portion of the dial disc 12 positioned in clearance 22a. By turning the key 17 and the cylinder 16 with the swing arm 22, the dial disc 12 and the stop member 13 are releasably interlocked, the border of the disc opening 12a forming a barrier closure for the passage 22 and the stop member 13 embraced to confine same, as shown in Figs. 3 and 6. The key 17 may then be removed and the locking mechanism 14 left effectively anchored in place, to prevent unauthorized dial disc 12 movement.

To release the locked disc 12, the key 17 is inserted into cylinder slot 16a and the cylinder 16 with the swing arm 22 turned back to releasing position as illustrated in Fig. 7 thereby permitting the dismounting of the locking mechanism 14 from said effective position for allowing the dial 11 to be manipulated in the readily understood manner.

To restrict the rotatory movement of cylinder 16, so that the key locking and unlocking position can be readily determined, suitable means may be provided, such as a groove 16d extending 180° about the outer surface of the cylinder 16 in which a stud 24 rides, said stud 24 being fixedly mount-

ed to extend inwardly from the interior side of casing barrel 15 as shown in Fig. 5.

If desired the exterior side of the casing barrel 15 may be suitably ribbed as at 25 to provide convenient finger gripping means.

It is thus seen that there is provided a mechanism in which the several objects of this invention are achieved and which is well adapted to meet conditions of practical use.

As various possible embodiments might be made of the above invention, and as various changes might be made in the embodiment above set forth, it is to be understood that all matters herein set forth or shown in the accompanying drawings are to be interpreted as illustrative and not in a limiting sense.

Having thus described my invention, I claim as new and desire to secure by Letters Patent:

1. A locking mechanism for a telephone dial having a manually operated rotary mounted dial disc formed with circular spaced openings and a relatively stationary stop member normally located adjacent to and over the path of movement of one of said disc openings comprising a casing having a leading end, a ledge integrally formed to project from said leading end to provide a passage formed with a wall of said ledge at said leading end for confining said stop member in said passage when said mechanism is seated in an effective locking position on said member, a barrel movably mounted in said casing in spaced alignment with relation to said ledge, a swing arm having a free end extending to be positioned in and out of alignment with respect to the ledge and mounted to turn with an end of said barrel beyond said leading casing end, said arm when in alignment with respect to the ledge being in said effective locking position spaced from said ledge to provide a clearance slightly greater than the thickness of the dial disc with the dial disc releasably secured to the stop member against movement from the passage, said arm when out of alignment insertable into the dial disc opening, and a key locking means in the casing for turning the barrel with said arm in and out of said aligning position.

2. A locking mechanism for a telephone dial disc having an opening and rotary mounted with respect to a relatively stationary stop member positioned over the path of movement of said disc opening, said locking mechanism formed with a portion adapted to be seated against the stop member, a movable end carried by said portion, a swing arm mounted to turn with said end, said swing arm and end being insertable through the disc opening when mounted said mechanism in said seated position, and a ledge integrally formed to extend from said seating portion spaced from said end defining a passage with said dial disc for confining the stop member therein and providing clearance slightly greater than the thickness of the disc for extending said dial disc into the passage, said mechanism serving to turn the swing arm from said insertable position to a spaced aligning position of said end with respect to the ledge for releasably interlocking the dial disc to said stop member.

3. A lock for a manually operated telephone dial having a rotatable plate disc formed with an opening and a relatively stationary stop member positioned over the path of movement of said disc opening comprising a key locking and releasing mechanism having a casing formed with a leading end including a ledge integrally formed to extend from a leading end of said mechanism, and a

swingable arm actuated by said mechanism and mounted on said leading end spaced from the said ledge when in a locking position to form therebetween a passage for embracing and confining said stop member and a clearance slightly greater than the thickness of said plate disc between aligning end portions of said ledge and arm to permit the extension of said disc into said passage when said mechanism is in said locking position releasably interlocking the dial disc with the stop member against unauthorized relative movement.

4. In a device for seating against a relatively stationary stop member of a telephone dial having a manually operated plate formed with an opening which is rotatably mounted under said member, a mechanism for locking the dial plate to the stop member to prevent unauthorized use of the telephone comprising a casing barrel having a leading end, a key actuated cylinder journaled for turn movement in said barrel having a portion extending beyond said leading end and adapted to be received through the dial plate opening, a swing arm having a free end terminating said extended barrel portion mounted to turn therewith, and a ledge integrally formed to project from said barrel leading end spaced from the extending portion and of a length short of the path of movement of the free end, said arm when in spaced alignment with respect to the ledge providing a clearance slightly greater than the thickness of the disc for permitting the dial plate to pass therethrough, said locking mechanism when in effective seated position with the swing arm turned to align with the ledge forming an enclosed passage embracing the stop member for locking the dial disc against movement with respect to said stop member.

5. In a device for seating against a relatively stationary stop member of a telephone dial having a manually operated plate formed with an opening which is rotatably mounted under said member, a locking mechanism comprising a relatively stationary body portion formed with an integral ledge at a leading end thereof to provide seating means against the stop member on a side

thereof opposite to that facing the dial plate, and a key-actuated swing arm extending through the dial plate opening beyond said seating means on the side of the dial plate opposite to that facing the stop member, the path of movement of said swing arm being spaced from the ledge to provide slight clearance for passage of the dial plate, said swing arm when said mechanism is in an effective locking position aligning with the ledge for locking the dial plate against movement with respect to the stop member and said swing arm when in a released position extends away from said ledge to permit the removal of the mechanism by withdrawal of the swing arm through the dial plate opening.

6. The locking mechanism defined in claim 1 in which said casing is formed with flattened oppositely positioned exterior finger gripping surfaces.

7. The lock defined in claim 3 in which said mechanism has exterior means formed thereon for finger gripping thereof.

8. The device defined in claim 4 in which said casing barrel is of oval cross-sectional shape to provide flattened oppositely positioned exterior finger gripping surfaces.
